UNITED STATES PATENT OFFICE.

ALPHONSE F. DELBERT, OF NEW ORLEANS, LOUISIANA.

CANE-MILL.

No. 895,005.

Specification of Letters Patent.

Patented Aug. 4, 1908.

Application filed September 26, 1907. Serial No. 394,668.

To all whom it may concern:

Be it known that I, ALPHONSE F. DELBERT, a citizen of the United States, residing at New Orleans, in the parish of Orleans and 5 State of Louisiana, have invented new and useful Improvements in Cane-Mills, of which the following is a specification.

My present invention relates to improvements in mills especially of the type used in 10 sugar making, and it has for its object primarily to provide an improved housing wherein the sections which sustain the pressure of the rolls are tied or bound so effectually that liability to fracture or breaking of the housing 15 is minimized, and the size and weight thereof is materially reduced so that cost of manufacture and transportation thereof is lessened and the erection of the mills is facilitated, the thorough binding and reinforcing of the housing 20 enabling the lower rollers to be placed more closely so that a turn plate of smaller area and less resistance may be employed.

Another object of the invention is to provide an improved mode of mounting the 25 pressure regulator or ram on a housing of the character above described, whereby it may be conveniently accessible and a proper operation thereof is insured, and to provide improved adjusting or locking devices for the 30 turn plate whereby the latter may be adjusted with facility and easily locked to prevent movement thereof laterally, vertically or in an endwise direction.

To these and other ends, the invention consists in certain improvements, and combinations and arrangements of parts, all as will be hereinafter more fully described, the novel features being pointed out particularly in the 35 claims at the end of the specification.

In the drawings—Figure 1 represents a 40 central longitudinal section of a cane mill constructed in accordance with the present invention; Fig. 2 is an end elevation of the mill shown in Fig. 1, portions of the housing 45 being shown in section to illustrate the tie bolts for binding the sections in coöperative relation; Fig. 3 is a detail end view of the turn plate and its supporting bar.

Similar parts in the several figures are designated by the same numerals of reference. 50

My present invention, as previously stated, is especially adapted for use in connection with mills of the type used in the manufac-

ture of sugar, the cane being passed between rolls under heavy pressure which serve to express the juice from the cane, and by reason of the excessive pressure imposed upon the rolls, considerable difficulty has been experienced with the housings which develop fractures by reason of the spreading of the 60 rollers, and it is the primary object of the present invention to cure this defect.

The mill shown in the present embodiment of my invention, embodies a set of three rolls having their axes arranged in triangular relation, the cane passing between the upper roll 1 and the forward roll 2 in entering the mill, and is then transferred by means of the turn plate 3 to the rear roll 4, the crushed cane passing from the mill between the rear 70 and upper rolls. The housings which serve to support the rolls in proper relation each embodies in the present instance a core or center piece 5 which may be composed of a casting of suitable metal and is mounted on a 75 base 6 by means of which the mill is supported. The center core thus provided has a vertically opening box 7 in the top thereof to receive the halved bearing members 8 and 9 which coöperate with the journals of the upper roll, and the center core is also provided with recesses 10 and 11 at its front and rear to receive the journals of the corresponding 80 rolls and their respective journal bearings 12 and 13. The top of the core is suitably 85 formed to receive the upper bearing cap 14, the latter and the core having surfaces which engage one another when the parts are in proper relation, and the lower, front and rear corners of the cores are also adapted to receive the front and rear bearing caps 15 and 16 which are also adapted to obtain a firm seating against the core. These bearing caps are preferably composed of steel so treated as to possess a relatively high tensile strength, an 90 open hearth steel casting having been found suitable for the purpose.

The tendency of the rolls, of course, is to spread as the cane passes between them, the lines of force in the mill shown acting in triangular relation to one another, that is to say, in lines drawn through the axes of the three rolls, and these strains are sustained according to the present invention by bolts or other devices of relatively high tensile 100 strength which extend in directions parallel.

to the directions of the strains, that is to say, they are arranged in triangular relation in the present instance to correspond to the three directions in which the strains act, and 5 the binding or tying devices thus provided coöperate with the three bearing caps to firmly bind them in coöperative relation with the center core of the housing and to wholly sustain the lateral thrust of the rolls. Three 10 pairs of tie bolts 17, 18 and 19 are employed in the present instance which surround the center core of the housing and connect the bearing caps, these bolts being preferably arranged outside of the journals of the rolls 15 and extend through openings in the three sides of the center core, and through registering openings in the respective bearing caps, the ends of each bolt being preferably provided with nuts or equivalent tightening 20 or locking devices whereby the several bearing caps may be locked firmly in coöperative relation with the center core. The bolts are preferably made of steel of relatively high tensile strength, and they, together with the 25 three bearing caps, sustain the entire spreading tendency of the rolls, so that the center core which does not receive the tension, may be composed of a relatively light casting.

A housing constructed in accordance with 30 the present invention enables the pressure regulating ram to be mounted in an improved manner for the reason that the upper bearing cap is in firm engagement with the center core of the housing and consequently it cannot 35 not tilt by reason of the unequal pressures between the upper roll and the front and rear rolls, and thus it affords a mounting for the ram that will maintain it in alignment and thereby prevent binding that would interfere 40 with its movements. In the present instance the fluid chamber or cylinder 20 is formed in the lower side of the upper bearing cap, the ram or plunger 21 being arranged to move downwardly from the underside of the 45 cap and bear upon the upper side of the bearing which coöperates with the journal of the upper roll, the degree of pressure or the range of movement of the ram being regulated by liners 22, which may be composed of thin 50 sheets of steel or other suitable material which are inserted in a recess 23 in the upper side of the bearing. The pressure regulating ram when so mounted is not only conveniently accessible for inspection or other purposes, but it leaves the under side of the 55 housing unobstructed so that a juice pan 24 may be placed between the housings and under the rolls, and provided with a pair of laterally extending spouts 25 and 26 which 60 extend immediately beneath the housings and communicate with gutters 27 and 28 which serve to conduct the juice expressed from the cane to any suitable point.

The bearings 12 and 13 of the front and 65 rear rolls, respectively, may be adjusted by

means of wedges 29 and 30, those edges of the bearings which coöperate with the wedges being preferably inclined to coöperate with the inclined surfaces of the wedges and the outer sides of the latter preferably bearing against a pair of parallel surfaces 31 and 32 formed on the respective bearing caps. These wedges may be tightened in any suitable way, they being provided with bolts 33 and 34 in the present instance which extend to the exterior of the housing and are provided with tightening nuts 35 and 36.

The turn plate 3 which serves to strip the crushed cane from the front roll and transfer it to the rear roll is supported on a cross bar 80, 37 which extends between the housings and rests in openings provided therein for the purpose, the plate being inserted in a seat 38 formed in the top of the cross bar and having a beveled rear edge which coöperates with an undercut wall 39 at the rear of the cross bar, a bolt 40 extending upwardly from the lower edge of the cross bar serving to lock the plate in its seat. This turn plate is adjusted relatively to the front and rear rolls 90 by means of a pair of wedges 41 and 42 having parallel outer sides which coöperate respectively with the parallel vertical walls 43 and 44 of the openings in the housing in which the ends of the cross bar rest, the 95 proximate sides of the wedges being inclined or tapered in reverse directions to coöperate with correspondingly tapered or inclined surfaces on the turn plate supporting bar. In the present instance the wedges are enlarged toward their upper ends and they coöperate with a pair of reversely tapered surfaces 45 and 46 on the cross piece and the wedges may be adjusted vertically and independently of one another for the purpose of 100 shifting the turn plate forwardly and rearwardly by means of bolts 47 and 48 which are attached to the respective wedges and extend downwardly into a recess 49 in the housing, the nuts 50 and 51 coöperating with the respective bolts and serving as a means for adjusting the wedges and locking them in adjusted position.

Vertical adjustment of the turn plate may be effected by means of a pair of wedges 53 and 54 which rest beneath the ends of the cross bar, the lower sides of the wedges engaging substantially square surfaces of the housing, while the upper inclined surfaces thereof coöperate with correspondingly inclined surfaces 55 and 56 formed on the under side of the cross bar, bolts or other equivalent devices 57 and 58 serving to adjust these wedges and lock them in operative position. Tightening of the wedges 41 and 42 has a tendency to draw the cross bar downwardly into engagement with the wedges 53 and 54 and endwise movement of the cross bar is prevented by the inclined surfaces on its under side which engage the 130

supporting wedges, the oppositely tapered surfaces of the upper sides of the wedges presenting inclined planes which will resist end thrust of the bar for the reason that the latter cannot rise because of the locking action of the wedges 41 and 42. In mills constructed in accordance with the present invention, the front and rear rolls may be placed relatively close to one another for the reason that 10 there are no bolts or other obstructions which extend through the housing between the turn plate supporting bar and journals of the rolls, and this is advantageous, as it enables a turn plate to be employed that has a relatively small surface which engages the crushed cane as it passes between the rolls, the friction thus reduced enabling the mill to operate more economically.

A mill constructed in accordance with the 20 present invention is not liable to breakage under stress of the rolls for the reason that the strains are resisted by tension members which extend in directions parallel to the directions in which the strains act and they 25 wholly surround the journals of the rolls so that the latter cannot possibly spread, and the relatively small size of the sections comprising the housing reduces the weight of the parts to such an extent that they may be 30 made and transported cheaply and readily assembled. Moreover, the reinforced construction of the housing enables the front and rear rolls to be placed as close as may be desired, and consequently the width of the 35 turn plate may be considerably reduced so as to avoid undue friction while stripping the material from the front roll and transferring it to the rear roll.

The improved mounting for the pressure 40 regulating ram enables the actual pressure between the rolls to be determined with certainty, and it is in a conveniently accessible position, while the mounting for the turn plate enables the latter to be adjusted with 45 facility, and it is positively locked from movement.

What I claim is:—

1. A housing for three-roll mills having 50 surrounding tension members connected to one another separately from the core of the housing for sustaining the lateral thrust of the rolls.

2. A housing for cane mills adapted to receive the rolls in triangular relation, and reinforcing members surrounding the housing and arranged in corresponding triangular relation and connected to sustain a tension independently of the core of the housing.

3. A housing for three-roll mills having a 60 set of tie bolts surrounding it and arranged in triangular relation the said bolts being connected to one another separately from the core of the housing.

4. A housing for cane mills embodying a

set of triangularly placed bearing caps, and a 65 set of tie bolts arranged in triangular relation and connecting all the bearing caps to one another.

5. A housing for cane mills embodying an approximately triangular center core having 70 recesses in its corners to receive the roll journals, bearing caps adapted to fit the corners of the core, and tie bolts connecting all the bearing caps to one another for drawing the bearing caps into firm engagement with 75 the core.

6. In a cane mill, a housing embodying a central core having recesses to receive the roll journals in triangular relation, a set of bearing caps adapted to fit the corners of the 80 core and coöperate with the roll journals, a set of tie bolts connecting all the bearing caps to one another and surrounding the core, and a pressure regulating ram mounted in one of the bearing caps. 85

7. A cane mill embodying a housing adapted to receive the roll journals in triangular relation, bearing caps adapted to engage the corners of the housing, tie bolts arranged in triangular relation and connecting all the 90 bearing caps to one another, and a pressure regulating ram mounted on the upper bearing cap.

8. In a cane mill, a pair of housings, a turn 95 plate bar connecting the housings and provided with oppositely inclined surfaces on its under side and adjacent to its ends, and having its vertical sides tapered toward the top of the bar, wedges supported on the housing and coöperating with the respective inclined 100 surfaces at the under side of the bar, locking wedges movable vertically in each housing and provided with reversely inclined inner surfaces coöperating with the tapered sides of the bar, and means for drawing the locking 10 wedges toward the supporting wedges to lock the bar thereon.

9. In a cane mill, the combination with a pair of housings, and a set of rolls journaled 111 therein, the housings having openings therein between the journals of the lower rolls and provided with parallel vertical walls, of a turn-plate bar having inclined surfaces on its vertical sides, and locking wedges interposed 11 between the vertical walls of the said openings and the inclined surfaces of the bar.

10. In a cane mill, the combination with the housings, and a set of rolls journaled therein, the housings having openings therein between the journals of the lower rolls and 12 provided with parallel vertical walls, of a turn-plate bar having its ends resting in the openings of the housings and provided with oppositely inclined surfaces at its vertical sides, and having its under side inclined in 12 opposite directions in proximity to its ends, supporting wedges resting on the housings and having inclined surfaces coöperating

with those on the under side of the bar, and pairs of wedges having parallel outer sides coöperating with the vertical walls of the openings in the housings and provided with reversely inclined surfaces coöperating with the vertical sides of the bar, and means for adjusting and locking the said wedges.

In testimony whereof I have hereunto set my hand in presence of two subscribing witnesses.

ALPHONSE F. DELBERT.
